and John H. Wackwitz;

BY
John S. Flynn
ATTORNEY

UNITED STATES PATENT OFFICE.

HENRY E. J. WACKWITZ, OF PORT WASHINGTON, NEW YORK, AND JOHN H. WACKWITZ, OF LYNDHURST, NEW JERSEY.

BRUSH.

Application filed January 29, 1927. Serial No. 164,555.

Our invention relates particularly to brushes for paint and varnish. The main object is to provide improvements on the brush of Patent 1,277,508, dated September 5 3, 1918. In detail we have sought to simplify the construction and yet protect the parts from injury and from accidental operation.

Another object is to make it possible to 10 apply more power for the purpose of operating the prop or support.

According to our invention, we provide a prop or support independent of the bristles for supporting the brush in a standing position. This prop is normally housed within 15 the body and handle of the brush and is adapted to be, when the brush is not in use, in a position where it will bear the weight of the brush without injuring the bristles.

20 The operating means for this prop or support consists of a gear mounted or housed entirely within the body of the brush and provided with external crank arm by which it may be operated.

25 In the accompanying drawing we have illustrated one form of the invention.

Fig. 1 is a side view of the brush construction embodying our invention, part of the bristles being broken away to disclose the 30 tip of the prop and the inner operating mechanism being shown dotted.

Fig. 2 is a transverse sectional view of the construction.

Fig. 3 is a side view, part of the handle 35 and bristles being broken away.

Fig. 4 is a fragmentary sectional view.

The body 5 of the brush may be of any suitable material such as wood or metal, and made up of one or more parts.

40 The handle 6 may be of any suitable construction and secured to the body in any suitable manner.

The bristles 7 may be of any suitable type and secured or set in the body in any suitable 45 manner. Usually and preferably, the body and upper ends of the bristles will be enclosed and protected by means of a metal shell or band 8 which may serve as a part of the means of connection between the 50 bristles and the body.

The prop or support 9 is in the form of a rod or stem which may have any suitable form of lower end or tip adapted to rest upon a support when in the projected position shown in Fig. 1. This rod is movable

longitudinally of the body and handle in a passage 10.

The rod is adapted to be operated by a rotatable gear 11 which is housed in a recess in the body and provided with suitable teeth for frictional engagement with the stem of the supporting rod. The operating gear is provided with a transverse shaft 12 of suitable construction in the body and provided with an external crank arm 13. The other end of the shaft may be suitably locked or secured by a lock or nut 14. By means of this crank arm 13 power may be applied for rotating the gear member 11 and reciprocating the rod 9 so as to project or retract it as required.

The body is preferably provided with a projecting lug 15. This lug is preferably inclined at its opposite edges so as to facilitate the movement of the end of the crank arm on to it from either direction. This lug is also provided with two notches 16 and 17 adapted to receive a correspondingly shaped projection at the rear of the crank arm behind the knob or finger piece 18 so as to hold the crank arm in position and prevent it from accidentally rotating and further preventing the rod 9 from moving longitudinally.

A stop 19 may be provided between the notches 16 and 17 to limit the rotation of the crank handle. Obviously the crank handle may be on either end of the shaft 12. We also prefer to omit the teeth at the inner end of the rod 9 so as to prevent the rod from being pulled out entirely.

The rod 9 preferably has an enlargement 20 serving as a valve to close the lower end of the passage 10 when the prop is retracted and the brush in use so as to prevent entry 95 of paint or varnish.

In the position shown in Fig. 1, the supporting member is locked in its projected position, at which time the crank arm is seated in the recess 16. By rotating the 100 crank arm in a right-hand or clockwise direction, the rod may be retracted, and when the crank arm engages in the notch 17, the rod will be locked in its retracted position.

We claim:

1. A brush having a body with a handle, a prop rod longitudinally movable in the body and handle, a rotatable driving member entirely housed within said body and geared to said rod, said member having an operat- 110

- ing crank arm external to said body and rotatable alongside of the body to effect the movement of said rod and means for preventing accidental movement of said rod.
5. 2. A brush having a body with a handle, a prop rod movable within the body, a member rotatable within the body and connected to said rod, an external crank connected to said member and a raised boss having an inclined end on one side of the body and having a recess to receive a part of said crank, said crank having a projecting part adapted to slide up said inclined end and fit in said recess.
- 10
3. A brush having a body with a handle, a prop rod movable therin, an operating member within the body, an operating handle therefor outside of said body, operative means of connection between said handle and said operating member, said body having a projection with inclined ends and two recesses adapted to receive a part of the handle to hold the same in either of two positions, said handle having a projecting part adapted to slide over said inclined ends and fit in said recesses. 15
